FOLDING GOLF BAG

Henry B. Eging, Jacksonville Beach, Fla.

Application October 28, 1953, Serial No. 27,370

Term of patent 14 years

(Cl. D34—5)

To all whom it may concern:

Be it known that I, Henry B. Eging, a citizen of the United States, residing at Jacksonville Beach, in the county of Duval and the State of Florida, have invented a new, original, and ornamental Design for a Folding Golf Bag, of which the following is a specification, reference being had to the accompanying drawing, forming a part thereof.

Fig. 1 is a perspective view of a folding golf bag, showing my new design in folded position;

Fig. 2 is a perspective view thereof in unfolded position;

Fig. 3 is a side elevational view thereof in unfolded position, looking at the right side in Fig. 2;

Fig. 4 is a rear elevational view thereof in unfolded position;

Fig. 5 is a top plan view thereof in unfolded position; and

Fig. 6 is a fragmentary perspective view thereof, to an enlarged scale, looking at the upper left hand corner in Fig. 4.

I claim:

The ornamental design for a folding golf bag, as shown.
